ABSTRACT: A drive assembly for high speed boats of relatively great size having an engine mounted inboards and an outboard propelling system. The steering of the boat is effected by turning the outboard system about a substantially vertical pivot located outside the stern board of the boat. The outboard propelling system is furthermore adapted to be pivoted backwards relative to the course of the boat about one or more horizontal pivots. The outboard propelling system is secured to the inboard engine which has its shaft coaxial with the input drive shaft of the outboard propelling system. This input shaft extends through a hole in the stern board of the boat and is driven synchronously with the engine speed by means of an engageable and disengageable clutch provided between said shafts. The inboard drive shaft transmits torque by means of a mechanical transmission to a horizontal propeller unit rotatably mounted in the lower portion of the outboard propelling system. The propeller has a plurality of blades adapted to be turned between two end positions for alternative ahead and astern propulsion of the boat, the blades being hydraulically operable by a piston rod displaceably mounted in a portion of a propeller shaft, said portion of the propeller shaft being in the form of a hydraulic cylinder.

OUTBOARD PROPELLING SYSTEM COMPRISING AN ADJUSTABLE PROPELLER

The present application is a continuation of application Ser. No. 696,400 filed Jan. 8, 1968 and now abandoned.

This invention relates to a driving mechanism for high speed, comparatively large boats having an inboard suspended engine and an outboard propelling system. In particular the invention relates to such driving mechanisms in which steering of the boat is effected by turning the outboard propelling system about a substantially vertical pivot located outside the stern board of the boat and wherein the outboard propelling system is also adapted to be turned backwards in the direction of the course of the boat about one or more horizontal pivots.

Outboard propelling systems of this kind have previously been constructed for comparatively small boats having an engine power of between 50 and 150 HP. However, development has tended toward ever increasing sizes of boats, and the demand for outboard propelling systems for comparatively large pleasure boats, taxi boats and similar transport boats and landing boats for naval purposes has increased enormously during the last decade.

The reason therefore is believed to be due to the fact that an outboard propelling system considerably reduces the initial costs as compared with a conventional inboard installation in which a propeller shaft below the boat is connected to the engine via a bevel gearing or the like. Further, an outboard propelling system has considerable advantages from the point of view of handling and maneuvering and the navigability of an outboard propelling system-equipped boat in shallow water is superior to a boat having firmly attached drive members. Since the outboard propelling system usually is adapted to be turned backwards in the direction of course of the boat, damages to this system in case of grounding are eliminated or mitigated. If, nevertheless, the propeller casing or part thereof should be damaged the propeller assembly of most of the prior art outboard propelling systems can easily be turned upwards above the water line and exchanged or repaired.

Conventional outboard propelling systems coupled to inboard engines are constructed to be secured to the stern board of the boat. Consequently, all stresses caused by the propelling system are transmitted to the stern board which has to be provided with strong reinforcements.

Further, such propelling systems usually include some sort of a reduction gear which via a vertical drive shaft transmits the engine power to a propeller shaft which indirectly carries a propeller with a plurality of fixed blades. The direction of rotation of such a propeller must be reversible for alternative ahead and astern propulsion of the boat. For this reason prior art propelling systems are equipped with a reversing gear and a friction clutch or the like between the engine and the propelling system.

In small boats having a power requirement below 150 HP the inconvenience of the reversing gear is not as manifest as in larger boats. In larger boats having a power requirement above 200 HP it has hitherto been necessary in each individual case to install at least two separate carburetor engines side by side with each engine driving its own propelling system. Such a parallel drive has certain advantages from the point of view of maneuverability, but its inconveniences are above all too high initial costs and the difficulty of obtaining a satisfactory parallel drive. In addition, the parallel drive results in a considerable increase of weight, and the available space in the stern part of the boat is too much reduced and renders maintenance work on the driving engines more difficult.

It would of course be possible to replace the cooperating engines by a single engine, but the maneuverability of the boat having a propeller with fixed blades would be difficult and besides, the reversing gear with the connected or built-in friction clutch would be too expensive to produce.

The object of this invention is to provide easy maneuverability of relatively large high-speed boats having a power requirement between 100 and 300 HP with the use of a single driving mechanism comprising an inboard motor and an outboard propelling system. In its broadest aspect the invention is characterized by the combination of the following features:

the outboard propelling system is firmly attached to the inboard suspended engine the shaft of which is coaxial with an input drive shaft of the propelling system, which input shaft extends through a hole in the stern board of the boat and via an engageable and disengageable clutch disposed between said shafts can be speeded synchronously with the engine speed;

the inboard drive shaft transmits torque via a mechanical transmission to a horizontal propeller unit rotatably mounted in the lower part of the propelling system; and the propeller has a plurality of blades adapted to be turned between two end positions for alternative ahead and astern propulsion of the boat, said blades being hydraulically operable by a piston rod displaceably mounted in a portion of a propeller shaft which portion is in the form of a hydraulic cylinder.

The combination according to the invention which advantageously can be applied to pusher propellers as well as tractor propellers offers considerable advantages due to the fact that its components and functions are considerably simplified as compared with previously known combination inboard engines - outboard propelling systems. Neither an expensive reversing gear nor other gearings are required, and a friction clutch provided between the engine and the propelling system is much less complicated than the conventional disc clutch in propelling systems having a propeller with fixed blades.

With the propelling system firmly attached to the engine the installation in the boat is facilitated. Due to the elimination of the necessity of aligning the engine and the propelling system and of otherwise required readjusting of said parts the invention results in the advantage that the engine can be elastically suspended in the engine bed resulting in a more silent and smooth operation of the engine. In addition, the stern board is relieved and the reaction pressure of the propeller is taken in the engine bed in a combination according to the invention.

An additional advantage is due to the fact that the manual control of the end positions of the propeller blades for obtaining a favourable propeller performance in boats of different sizes and loads also results in a better fuel economy of the engine. In the combination according to the invention the engine is preferably a diesel engine which reduces the danger of fire onboard the boat and results in lower operating costs and higher reliability in operation as compared with a petrol engine.

Within the scope of the annexed claims the invention can be embodied in many different ways, and due to the great flexibility of the embodiment illustrated in the annexed drawings and described hereinbelow this embodiment is only an example of carrying the invention into effect.

In the annexed drawings, FIG. 1A is a longitudinal sectional view of the propelling system according to the invention attached to an inboard diesel engine, FIG. 1B shows a detail of FIG. 1A on an enlarged scale, FIG. 2 is a cross-sectional view taken along the line A-A in FIG. 1A and illustrates the members by means of which the outboard section of the propelling system can be turned laterally upwards into a position above the water line, FIG. 3 is a sectional view taken along the line B-B in FIG. 1B and illustrates the mechanical shifting mechanism for the propeller blades, FIG. 4 is a cross-sectional view along the line C-C in FIG. 1A and illustrates the members comprised in the steering mechanism of the propelling system, and FIG. 5 is a sectional view taken along the line D-D in FIG. 1A and shows how the steering operation is servo-controlled.

With respect to its characteristic function the propelling system according to the invention comprises an inboard section and an outboard section. By means of flanges and screws the inboard section is firmly attached to the flywheel housing of the engine 1. By means of a front bearing, not shown, and a rear attachment 3 the engine 1 is in a conventional manner elastically suspended in an engine bed in the stern part of a boat 4.

Provided between the output shaft, not shown, of the engine 1 and an input shaft 6 of the propelling system is a friction clutch 5 by means of which the input shaft 6 can be connected to and disconnected from the engine 1. The friction clutch is of any suitable conventional type and need not be described in detail.

The clutch 5 is enclosed in a case 7 which is the external cap of the inboard section of the propelling system. By means of the above named flanges and screws, not shown, the clutch case 7 is firmly attached to the flywheel housing 2 of the engine. Consequently, the flywheel housing supports the whole of the propelling system. Beginning from the flanged connection with the flywheel housing 2 the clutch case is first conical and then merges into a sleeve-shaped portion 7a which extends through an upper hole in the stern board 8 of the boat.

In order to render possible inspection of the clutch 5, the upper portion of the wall of the clutch case 7 has an opening which in normal operation is closed by a protective cover 9.

At the outer end of the conical portion of the clutch case 7 there is provided an integral downwardly extending shield 7b secured to two brackets 10 each of which has mounted thereon a supporting rod 10a. These supporting rods extend through lower holes in the stern board 8 of the boat and their outer ends bear on the outboard section of the propelling system.

The three holes in the stern board 8 are sealed by elastic sealing rings 11 and 12 which are secured to the stern board and surround the sleeve 7a and the rods 10a, respectively.

Rotatably mounted in the sleeve 7a of the clutch case is a unit held together by axial screws, not shown, and consisting of two hubs 13 and 14 extending from different sides of the sleeve 7a and located one within the other. Each hub is connected to a ball bearing 15 and 16, respectively, by means of which the input shaft 6 is mounted in the propelling system.

By means of splines a shaft 17 is displaceably mounted in the outer end of the shaft 6. By means of a double universal joint 18 and flanged screw joint 19 the shaft 17 is relatively nonrotatably connected to a rotatably mounted external drive shaft 20 which is aligned with the shafts 6 and 17 and the mounting of which will be described hereinbelow.

The hub 14 has an external flange 14a which by means of a flange and screws, not shown, is connected to a front casing 21 of the outboard section of the propelling system. The outboard section is rotatably mounted as a unit relative to the inboard clutch case 7 secured to the engine 1. To this end the sleeve 7a of the clutch case is provided with a vertical screw 31 which along a secant extends through the wall of the sleeve 7a and is in mesh with a peripheral thread on the hub 13. If the screw 31 is turned by a crank, not shown, the composed bearing unit 13, 14 in the sleeve 7a will be turned together with the outboard section of the propelling system.

The front casing 21 carries the control means of the outboard section which means are in the form of a unit composed of a plurality of individual parts which substantially comprise a steering mechanism 28, a rear casing 26 including power transmission means, and a propeller assembly 24. For the sake of convenience this unit will be termed hereinbelow control casing 22.

The control casing 22 can carry out two different kinds of turning movement relative to the front casing 21, namely for performing the steering action and, for the sake of safety, for preventing too great damages to the propeller assembly in case of grounding. In both cases a V-shaped steering fork 27 comprised in the steering mechanism 28 is the connecting member between the two casings 21 and 22.

As will be seen from FIG. 4, the steering fork 27 is movably mounted on two pivots 25 each of which extends through a bearing member 21a at the respective vertical wall of the front casing 21 and is received in a through hole in the respective end of the limb of the V-shaped steering fork inside the front casing 21.

The steering fork 27 carries the other members of the steering mechanism 28. A U-shaped reinforced bearing bracket 32

is mounted for turning movement on a vertical pivot 23 which is axially nondisplaceably mounted for turning movement in a through hole coinciding with the vertical axis of symmetry of the V-shaped steering fork 27. The bearing assembly comprises ball bearings 33 secured to the ends of the respective fork limbs. The upper limb 32a of the bearing bracket 32 is mounted above the bifurcation of the steering fork 27 and the lower limb 32b is fitted into a horizontal recess in the steering fork 27.

10 The bearing bracket 32 has two double attachments 32c which extend from the web of the bracket and by means of two pins 35 or the like are connected to two hydraulic cylinders 35 adapted to be turned about the pins 35. The piston rods 34a of the hydraulic cylinders are received in external recesses in the lower sides of the steering fork 27 and are held therein by through pins 36 which by means of locking pins are secured in the steering fork 27. Under the action of the hydraulic cylinders 34 the bearing bracket 32 is turned about the vertical pivot 23, and a unit secured by means of screws, not shown, to the bearing bracket 32 and consisting of the rear casing 26 and the propeller assembly 24 takes part in this turning movement.

25 The mode of operation of the hydraulic cylinders 34 is known in the art, and the special embodiment of the members comprised in the propelling system will be explained in connection with the following description of the supply of servo-operating hydraulic fluid to the means for effecting ahead and astern propulsion of the boat 4.

30 There are required four oil outlet conduits, not shown, from the control members of the boat. These conduits communicate in a conventional manner with a corresponding number of inlet openings I-IV in the wall of the inboard part of the sleeve 7a of the clutch case. These inlet openings communicate with internal ducts in the hub 14. The ducts open at the flange 14a and extend into closed ducts, not shown, in the wall of the front casing 21. From FIG. 4 it will be seen that two pairs of ducts at the flange 14a are located on either side of a line of symmetry. The ducts are separated from each other 35 and provide a pair of inlet and a pair of outlet passages of opposite functions. In the following, only one duct of each kind will be described.

35 The ducts I and III enclosed in the front casing 21 communicate with radial inlets to eccentrically disposed axial ducts in the pivot 24. The last named ducts are closed at their respective ends but communicate via radial outlet openings with ducts in the steering fork 27. The duct I opens into a dead end hole in the pin 36. This dead end hole communicates radially with a through hole in the piston rod 34a mounted on the pin 36 and opens into the high pressure chamber of the hydraulic cylinder 34, which high pressure chamber is defined between the piston 34b and the rear end wall 34c of the cylinder.

50 Upon supply of pressure fluid through the conduit I into the high pressure chamber the hydraulic cylinder 34 will be displaced to the right as viewed in FIG. 5 and turn the bearing bracket 32 and the entire control casing 22 about the pivot 23. Since both hydraulic cylinders are cooperating with each other, the movement of the other hydraulic cylinder 34 will be in the opposite direction. The low pressure chambers of the hydraulic cylinders, i.e. the chambers between the pistons and the front end walls through which the pistons are displaceable, communicate with each other through a conduit 34d which permits free flow of air enclosed in the respective low pressure chamber and prevents counter pressures from acting during the relative displacements of the pistons.

55 The duct III in the pivot 25 and steering fork 27 communicates radially with one of two eccentrically located axial ducts in the central pivot 23 of the steering fork. These axial ducts are closed at one end and communicate via radial outlet openings with two fluid conduits 54, 55. These conduits are connected to the upper limb 32a of the bearing bracket and to the rear casing 26 and secured to two ducts in the propeller assembly 24. Through these ducts III and IV the pressure of the hydraulic fluid in the propeller assembly 24 is controlled so

that shifting of the propeller blades 51 for ahead and astern propulsion is entirely servo-controlled. This control will be described hereinbelow with reference to the propeller assembly 24.

Referring to the description of the relative turning movement of the steering mechanism 28 and the control casing 22 with respect to the front casing 21, the previously named relative turning movement which occurs if the propeller assembly 24 strikes a ground will now also be described in detail.

The control casing 22 which is movably mounted on the two transverse horizontal pivots 25 is normally fixed in operative position relative to the front casing 21 by means of a safety cotter 29. The safety cotter connects two lugs on the steering fork 27 with a lower flange 21b of the front casing. The safety cotter 29 is dimensioned such that it will be shorn off if the propeller assembly 24 strikes a ground, the result being that the entire control casing 22 will be turned backwards about the pivots 25.

To enable this relative turning movement the boundary lines and surfaces of the front casing 21 and control casing 22 must be curved with the centre of curvature coinciding with the axis of movement. In FIG. 1A this is represented for horizontal turning movements by the circular arcs for the respective casings 21 and 22, the common centre of said arcs lying on the common axis of the pivots 25.

The central member in the control casing 22 is the rear casing 26 which comprises a front end wall 27a and a rear end wall 26b in which the outer drive shaft 20 of the propelling system is mounted in ball bearings 37 and 38, respectively. The ball bearing 37 is mounted in a hub 39, and the ball bearing 38 is mounted in a hub 40. Both hubs have eccentric bearing holes and their flanges are by means of screws, not shown, secured to the respective end walls 26a and 26b.

A contact surface on the outside of the inner end wall 26a and located below the bearings 37, 39 holds the rear casing 26 in contact with the bearing bracket 32 by means of screws, not shown. Due to the fact that the rear casing 26 in a manner not specifically described carries the external caps 46, 47 of the control casing 22 and via a base 26c which interconnects the lower ends of the end walls and by means of screws, not shown, is rigidly secured to the propeller assembly 24, the entire rear part of the control casing 22 is attached to the bearing bracket 32.

Located between the end walls 26a and 26b and axially held in position by two spacer sleeves 41 and 42 abutting against the ball bearings 37 and 38, respectively, is a sprocket 43 secured by splines to the outer drive shaft 20. An endless chain 44 transmits the input torque of the propelling system from the sprocket 43 to a sprocket 45 mounted in the propeller assembly 24. The chain can be stretched by turning the hubs 39, 40 in the end walls 26a and 26b, respectively.

The propeller assembly 24 comprises a casing 52 the upper part of which is secured to an intermediate part 30 and the lower part of which is secured to a fin 53. By means of screws, not shown, extending through the base 26c the top end of the intermediate part 30 is attached to the underside of the rear casing 26 so that the propeller assembly 24 as a whole is rigidly connected to the steering mechanism 28 of the propelling system.

The rotary members of the propeller assembly 24 are movably mounted in the casing 52 and rotated by the chain 44 which engages the sprocket 45 and runs through recesses in the intermediate part 30 and in the top wall of the propeller casing 52. By means of splines the sprocket 45 is relatively non-rotatably mounted on a shaft 56 which by means of two roller bearings 57, 58 is rotatably mounted in the casing 52. Axial movement of the sprocket 45 is prevented by a locking ring 49 which by means of screws, not shown, and via the inner race of the roller bearing 57 and a spacing sleeve 50 clamps the sprocket 45 against a shoulder of the shaft 56.

The front end of the shaft 56 has a flange to which a propeller unit 60 is secured by screws. The diameter of the shaft 56 is backwardly stepwise reduced, and the rear part of

this shaft is of tubular shape and has a central through hole 56a in which a tube 59 of considerably smaller diameter than the diameter of the hole 56a is inserted between a pipe plug 61 screwed into the rear end of the shaft 56 and a duct guide 62 screwed into a widened hole in the front end of the shaft 56.

The tubular rear part of the shaft 56 extends through a chamber IV separated in the casing 52. This chamber is defined by a sealing ring 63, a spacer sleeve 64 and a hub 65. The chamber IV opens into a chamber III in the hub 65. The spacer sleeve 64 and the hub 65 are axially locked by a nose 78 secured to the rear end of the casing 52. As will appear from the reference numerals of the respective separated chambers and from FIG. 1B these chambers communicate through substantially radial ducts in the members 64 and 65 and through inner internal ducts in the propeller casing 52 and the intermediate part 30 with the previously described ducts or conduits III and IV for the supply of hydraulic fluid to the propeller assembly 24.

The chamber IV opens through radial holes in the tubular portion of the shaft 56 into the annular axial duct formed by the central hole 56a and the tube 59 so that the ducts III and IV extend concentrically through the shaft 56 to the duct guide 62.

At the front end the part of the shaft 56 located outside the duct guide 62 is in the form of a hydraulic cylinder 56b which has a fixed end wall 66 through which a piston rod 67 displaceably mounted in the propeller unit 60 extends into the hydraulic cylinder 56b. The inside end of the piston rod 67 is secured to a piston 68 in the hydraulic cylinder 56b. A tubular neck portion of the duct guide 62 is received in a dead end hole in the piston rod 67.

Through internal holes 62a in the duct guide 62 the annular duct IV communicates internally with the tubular neck portion of the duct guide, and via radial holes in the piston rod 67 near the piston 68 and via the axial dead end hole the final communication is established with one chamber of the hydraulic cylinder 56b. The duct III in the tube 59 communicates through internal holes 62b in the duct guide 62 directly with the other chamber of the hydraulic cylinder 56b.

Upon increase of pressure in the chamber III or IV of the hydraulic cylinder 56b the piston 68 and the piston rod 67 will be moved into either of two end positions in the hydraulic cylinder 56b and the propeller unit 60.

The propeller unit comprises a rear bearing sleeve 69 and a front bearing sleeve 70, which sleeves by means of flanges and screws, not shown, are secured to each other and together carry the other members comprised in the propeller unit 60. By means of screws extending through the front flange of the shaft 56 the propeller unit 60 is connected to the rotary shaft 56 via the bearing sleeve 69.

At their common boundaries the bearing sleeves 69, 70 are in the form of collar-shaped bearing cups in which the propeller blades 51 are rotatably mounted and prevented from displacement by plates 51a secured to the inner bearing ends of the respective blades 51. Provided eccentrically on the underside of each plate 51a is an adjusting pin 51b by means of which the angular positions of the propeller blades 51 can be adapted to the movement of the piston rod.

The piston rod 67 is displaceably mounted in the end walls of the bearing sleeves 69 and 70 and has secured to it a shifting member 72 located between said end walls. The shifting member has three forklike grooves on its irregular circumference which grooves receive the adjusting pins 51b. Upon displacement of the piston rod 67 and the shifting member 72 the adjusting pins 51b are acted upon and thereby turn the propeller blades 51 relative to the bearing sleeves 69, 70.

The shifting movement of the propeller blades 51 is limited by the contact of the piston rod 67 with adjustable abutments in the respective end positions. The inner abutment or stop member is the duct guide 62, and the outer abutment or stop member is a stop screw 74 which is threaded into the hublike outer portion 70a of the front bearing sleeve and is locked in adjusted stop position by a locking screw 75.

Secured to the end wall of the bearing sleeve 70 by means of screws, not shown, and mounted on the hub 70a is a nose 71. Through a stepped central hole in the nose a tubular sleeve 76 is threaded into the hub 70a outside the screws 74, 75. Inserted into the tubular sleeve 76 is a detachable plug 77. In order to adjust the top position of the screw 74, the plug 77 is removed and different lock keyes are inserted into the tubular sleeve 76 for adjusting the respective screws 74 and 75 into desired positions.

I claim:

1. A drive unit for a vessel having a hull and a stern board comprising a power plant mounted in said hull, a drive shaft extending rearwardly therefrom, an outboard propelling assembly, said assembly including a forward section and an after section turnable in a horizontal plane about a vertical axis and in a vertical plane about a transverse axis relative to said forward section, a drive shaft extending forwardly from said assembly, a universal joint disposed in said last-mentioned drive shaft to permit rotation of said after section, means for coupling said drive shafts coaxially, a first sleeve fixed to said power plant and concentrically mounted about said coupled drive shafts, said sleeve passing through an opening in the stern board so that substantially no thrust is imparted to said stern board, a second sleeve fixed to said forward section of

said propelling assembly and mounted in concentrically nested relationship with said first sleeve, means for rotating said second sleeve relative to said first sleeve to rotate said assembly about the axis of its drive shaft, a propeller unit fixed to and depending from the after section of said propelling assembly, propeller blades mounted in said propeller unit, a vertically disposed steering post turnably connecting the forward section with the after section, beneath the universal joint, hydraulic means for rotating said after section about said vertical steering post to thereby rotate said propeller unit for steering the vessel, means for driving the propeller blades by the drive shaft of the propelling assembly and hydraulic means varying the pitch of said propeller blades from full forward thrust to full rearward thrust, said hydraulic steering means and said hydraulic blade pitch varying means comprising annular grooves provided in one of said sleeves to form, together with the other of said sleeves, a number of annular hydraulic fluid distributing channels interconnected with the hydraulic steering means and said hydraulic blade pitch varying means respectively, whereby said steering means and said blade pitch varying means may be operated independently of the angular position of the after section about the axis of the drive shaft in relation to the forward section.
